(57) **CLAIM**

The ornamental design for a urine shield as shown and described.

DESCRIPTION

FIG. 1 is a perspective view of the urine shield.

FIG. 2 is left side view of the urine shield.

FIG. 3 is a right side view of the urine shield.

FIG. 4 is a front view of the urine shield.

FIG. 5 is a back view of the urine shield.

FIG. 6 is a top view of the urine shield.

FIG. 7 is a bottom view of the urine shield; and,

FIG. 8 is a perspective view of the urine shield in use. The broken lines included in the drawings are for the purpose of illustrating environmental structures and form no part of the claimed design.

1 Claim, 7 Drawing Sheets
